DINING TABLE ACCESSORY

Guillermo Solomon Padial, Caracas, Venezuela

Application September 27, 1955, Serial No. 536,926

5 Claims. (Cl. 45—68.3)

This invention relates to a dining table accessory, and more particularly to a tablecloth.

Heretofore it has been customary to use separate plates for dining, which plates are subjected to breaking, hard to clean, or if discardable plates are used, expensive. Separate mats have been proposed having plates built therein. These mats did not cover the entire table and also had to be individually cleaned.

It is an object of the present invention to provide a tablecloth having plates as an inherent part thereof.

It is a further object of the present invention to provide a tablecloth which may be readily cleaned.

Yet another object of the present invention is to provide a tablecloth having all of the desired advantages which is nevertheless inexpensive to manufacture and easy to produce.

Other objects and advantages are set forth in the accompanying specification taken in conjunction with the accompanying drawings, in which:

Fig. 1 is a perspective view of the dining table accessory of the present invention;

Fig. 2 is a sectional view taken along the lines 2—2 of Fig. 1;

Fig. 3 is a broken top view of one individual plate on the dining table accessory of the present invention;

Fig. 4 is a section taken along the lines 4—4 of Fig. 3;

Fig. 5 is a section of a modified form of the present invention;

Fig. 6 is a section of the supporting strip used in the modified form of the present invention shown in Fig. 5;

Fig. 7 is a section of still another modified form of the present invention; and

Fig. 8 is a section of the disk used in the modified form of the invention shown in Fig. 7.

Referring to the drawings, there is shown a dining table accessory 10 in the form of a cloth 11 which covers the entire surface of the table 12. The cloth comprises a relatively large flexible sheet of impervious resilient material which is adapted to be spread on a table and over the ends thereof, as shown. At spaced intervals in the cloth and as an integral part thereof, I have provided formed portions 13 in the shape of dishes adapted to hold food and the like. The formed portions are made of and are a part of the relatively large flexible sheet of impervious resilient material. The sheet of material is also relatively thick in the preferred embodiment of my invention so that it will hold all types of food including soups, and the like. The tablecloth made according to the present invention is particularly adapted for use in feeding children and for use on picnics and the like. The tablecloth may be washed in its entirety with the same cleansing operation also cleaning the plates themselves, which as aforesaid are an integral part of the tablecloth.

In the modified form of the present invention shown in Fig. 5, the tablecloth 15 is provided with formed portions in the shape of dishes 16 which are adapted to hold food. In this modification the tablecloth may be of relatively

2

thin material. The formed portion, as shown, has a raised edge providing an annular groove 18. In order to maintain the shape of the dishes with this relatively thin material, a ring 17 is provided and accommodated within the groove 18. The ring is made of impervious flexible washable material which may be secured in the groove or the ring may be removable so that it can be detached prior to washing the cloth and the integral plates thereof.

In the modification of the present invention shown in Fig. 7, the tablecloth 20 may be made of any suitable sheet of flexible impervious resilient material. The formed portion 21 in the shape of a dish is provided and adapted to hold food or the like. For use where it is desired to cut the food, a disk 22 of relatively hard easily washable material, such as a hard plastic, metal, or the like, is preferably bonded to the tablecloth in the formed portion covering the entire surface of the formed portion 21. When this disk is utilized, according to the present invention, a knife or other sharp instrument may be used without damaging the cloth itself. If desired, the disk may comprise a removable insert of relatively hard material.

It will be seen that I have provided a new and novel tablecloth adapted to cover the entire table and to be draped over the sides so that no food may be spilled on the table itself and having formed plate-shaped portions as an integral part of the tablecloth. This cloth including the dish portions may be easily washed and is especially adapted for use in outdoor picnics or the feeding of children whereby separate plates which are subject to damage or expensive discardable plates may be dispensed with.

While I have described the invention in some detail, it will be understood that variations and modifications may be made without departing from the spirit of the invention or the scope of the appended claims.

I claim:

1. As a new article of manufacture, a dining table accessory comprising a relatively large, flexible sheet of impervious resilient material adapted to be spread on a table and draped over the ends thereof in the manner of a tablecloth, said sheet having flexible formed portions in the shape of dishes, adapted to hold food and the like, said portions being devoid of undercuts.

2. As a new article of manufacture, a dining table accessory comprising a relatively large, flexible sheet of impervious resilient material adapted to be spread on a table and draped over the ends thereof in the manner of a tablecloth, said sheet having flexible formed portions in the shape of dishes, adapted to hold food and the like, said formed portions having raised edges providing annular grooves, and being devoid of undercuts; and rings accommodated in said annular grooves to reinforce said raised edges and prevent collapsing thereof.

3. The invention as defined in claim 2 in which the sheet is relatively thin.

4. The invention as defined in claim 2 in which said rings are removable.

5. As a new article of manufacture, a dining table accessory comprising a relatively large, flexible sheet of impervious resilient material adapted to be spread on a table and draped over the ends thereof in the manner of a tablecloth, said sheet having flexible formed portions in the shape of dishes but devoid of undercuts, adapted to hold food and the like; and disks of relatively hard material carried in said formed portions.
